No. 800,437.

PATENTED SEPT. 26, 1905.

R. H. FRAY
RAIL CHAIR.
APPLICATION FILED JAN. 16, 1905.

UNITED STATES PATENT OFFICE.

REUBEN HENRY FRAY, OF TRAVER, CALIFORNIA.

RAIL-CHAIR.

No. 800,437.

Specification of Letters Patent.

Patented Sept. 26, 1905.

Application filed January 16, 1905. Serial No. 241,262.

To all whom it may concern:

Be it known that I, REUBEN HENRY FRAY, a citizen of the United States, and a resident of Traver, in the county of Tulare and State 5 of California, have invented a new and Improved Rail-Chair, of which the following is a full, clear, and exact description.

The object of the invention is to provide a new and improved rail-chair arranged to prevent spreading of the rails, especially along 10 sharp curves, to securely join adjacent rails without the use of fish-plates and the like, and to permit convenient removal of a worn-out rail to be replaced by a new one.

15 The invention consists of novel features and parts and combinations of the same, as will be more fully described hereinafter and then pointed out in the claims.

A practical embodiment of the invention 20 is represented in the accompanying drawings, forming a part of this specification, in which similar characters of reference indicate corresponding parts in all the views.

Figure 1 is a perspective view of the improvement. Fig. 2 is a cross-section of the 25 same. Fig. 3 is a like view of a modified form of the improvement. Fig. 4 is a perspective view of a modified form of the improvement, and Fig. 5 is a plan view of the 30 same.

The improved rail-chair, as illustrated in Figs. 1 and 2, is provided with a metallic base-plate A, formed on its top with a slightly-inclined seat A' for the base of a rail B to rest 35 on to slightly tip the rail, especially along a curve, and the outer side of the said rail B is engaged from the base to the top thereof by an abutment C, so as to prevent the rail from spreading outwardly.

40 The abutment C is provided with a bottom C', resting on the rear portion of the base-plate A and fitting into a hook A², formed on the outer end of the said base-plate. One or a plurality of transverse ribs C² connect the 45 abutment C with its integral bottom C', so as to render the said abutment as strong as possible for securely holding the rail in place—that is, against outward movement, as above mentioned.

50 Portions of the inner end of the base-plate A are curved upwardly over the top of the inner portion of the base of the rail B to terminate in lugs A³, connected by bolts D with the abutment and the web of the rail, so as to 55 hold the rail against inward movement. The portion of the base A not turned up at its in-

ner end is extended transversely, as at A⁴, to form a connecting-bar adapted to be interlocked at A⁵ with the corresponding bar A⁴ of the opposite chair, as plainly illustrated in Fig. 1.

Spikes E are driven through the bottom C' and the rear portion of the base-plate A into the tie F to securely hold the chair against lateral movement, and the under side of the 65 base-plate A is also preferably provided with depending pins A⁶, adapted to be driven into the tie F. Spikes E' are driven through the bar A⁴ to engage with their heads the base of the rail between the lugs D, and spikes E² are 70 also driven through the said bar A⁴ adjacent to the interlocked ends A⁵.

By the arrangement described the rail is securely held in place both against longitudinal and transverse movement, and by having 75 the exceedingly strong abutment C extending the entire outside of the rail B the latter is prevented from spreading, especially around sharp curves.

If desired, the base-plate G, as shown in Fig. 3, may be made integral with the abutment G', and in this case a separate plate H is provided instead of the lugs A³, and this plate H is connected by bolts I with the abutment G' to hold the rail against inward movement.

The device above described and shown in Fig. 3 is especially serviceable for use on the joint of adjacent rails, as the plate H serves as a fish-plate.

In the modified form illustrated in Figs. 4 and 5 the abutment J and the base-plate K are wedge-shaped in plan view to allow of conveniently sliding the abutment in position on the base-plate K in the direction of 90 the length of the rail. In order to hold the abutment J against longitudinal movement, the base-plate is provided with an upturned flange K', engaged by a bolt L, also passing through the adjacent strengthening-rib 100 J' of the abutment. The base-plate K is also provided with a downturned flange K², spiked to the side of the tie N. The hook K³ of the base-plate K and a portion of the abutment J are cut out to allow for the passage of 105 a spike to secure the parts in position on the tie N.

Having thus described my invention, I claim as new and desire to secure by Letters Patent—

1. A rail-chair having an abutment fitting the outside of the rail from the base to the

top of the rail, the abutment having an integral bottom, a plurality of transverse ribs integrally connecting the bottom and the abutment, for bracing the abutment, and 5 means for fastening the abutment in position.

2. A rail-chair having a base-plate provided with a hook, an abutment held on the base-plate and fitting the outside of the rail, 10 the outer end of the abutment engaging the said hook, and means for fastening the abutment to the base-plate to prevent longitudinal movement of the abutment.

3. A rail-chair having a base-plate formed 15 with a hook on its outer end and having a seat for the rail-base, an abutment on the said base-plate fitting the outside of the rail, the outer end of said abutment engaging the said hook, means for fastening the abutment 20 to the base-plate, and means for fastening the base-plate to a tie.

4. A rail-chair having a base-plate formed with a hook on its outer end and having a seat for the rail-base, an abutment on the 25 said base-plate fitting the outside of the rail, the said abutment having a bottom resting on the base-plate and engaging the said hook, the bottom and the abutment being connected with each other by a plurality of 30 transversely-extending ribs, and means for fastening the abutment to the base-plate to prevent longitudinal movement of the abutment.

5. A rail-chair having a base-plate formed 35 with a seat for the rail-base, and an abutment on the said base-plate, fitting the outside of the rail from the base thereof to the top of the rail, the said abutment having a

bottom resting on the base-plate and engaging a hook on the outer end thereof, the said 40 bottom and the abutment being connected with each other by a plurality of transversely-extending ribs.

6. A rail-chair having a base-plate provided with a hook, an abutment held on the base-plate and fitting the outside of the rail, 45 the outer end of the abutment engaging the said hook, the said base-plate and abutment being wedge-shaped in plan view, and means 50 for fastening the abutment to the base-plate, to prevent longitudinal movement of the abutment.

7. A rail-chair having a base-plate provided with a hook, and an abutment held on the base-plate and fitting the outside of the 55 rail, the outer end of the abutment engaging the said hook, the said base-plate and abutment being wedge-shaped in plan view, the 60 said hook and abutment having cut-out portions for the passage of a spike.

8. A rail-chair having a base-plate provided with a hook, an abutment held on the base-plate and fitting the outside of the rail, the outer end of the abutment engaging the 65 said hook, the said base-plate and abutment being wedge-shaped in plan view, and means for fastening the base-plate to the side of the tie.

In testimony whereof I have signed my name to this specification in the presence of 70 two subscribing witnesses.

REUBEN HENRY FRAY.
